UNITED STATES PATENT OFFICE.

CHARLES D. McCONNELL, OF OSKALOOSA, IOWA, ASSIGNEE OF ONE-HALF, TO JOHN M. BRYSON, OF OSKALOOSA, IOWA.

AUTOMATIC HOSE-REEL.

1,206,563.

Specification of Letters Patent. Patented Nov. 28, 1916.

Application filed June 8, 1915. Serial No. 32,985.

To all whom it may concern:

Be it known that I, CHARLES D. McCONNELL, a citizen of the United States, residing at Oskaloosa, in the county of Mahaska 5 and State of Iowa, have invented a new and useful Automatic Hose-Reel, of which the following is a specification.

This invention has reference to hose reels, and its object is to provide a hose reel 10 which will automatically wind hose thereon with the hose constantly attached thereto and by means of which a supply of fluid may be delivered by the hose when the latter is drawn out.

15 The present invention is intended more particularly for use in garages and is to be used to supply air under pressure for charging pneumatic tires or for cleaning or other purposes. The structure is also adapted for 20 use for supplying water for washing automobiles and for other purposes. While the hose reel is useful in connection with either air or water as the fluids, it will be considered for convenience of description as 25 being used for supplying air under pressure, but it is to be understood that such restriction in the description in no wise limits the use of the invention to supplying air to the exclusion of other fluids.

30 The present invention is an improvement upon the device shown in Patent No. 1,151,890, for a hose reel granted to me on August 31, 1915, and in general the improvement consists in a construction whereby 35 the cost of manufacture is greatly reduced and the operation is decidedly simplified, without, however, sacrifice of some of the principal features of the structure shown in the aforesaid application.

40 The present invention provides a hose reel mounted for rotation in a casing from which one end of the hose having the other end attached to the reel may be withdrawn, such withdrawal causing a rotation of the 45 reel. Coupled to the reel is a spring-actuated member in a manner to put the spring under tension as the hose is withdrawn, so that on the release of the hose it will be automatically wound upon the reel.

50 The invention will be best understood from a consideration of the following detailed description, taken in connection with the accompanying drawings forming a part of this specification, with the further under-

standing that while the drawings show a 55 practical form of the invention, the latter is not confined to any strict conformity with the showing of the drawings, but may be changed and modified so long as such changes and modifications mark no material departure from the salient features of the invention as expressed in the appended claims.

In the drawings: Figure 1 is an edge elevation with parts in vertical section of a 65 hose reel constructed in accordance with the present invention. Fig. 2 is a section on the line 2—2 of Fig. 1. Fig. 3 is a rear face view of the spring drum with the cap plate of the spring chamber removed. Fig. 70 4 is a section on the line 4—4 of Fig. 3, with the cap plate in place. Fig. 5 is a longitudinal diametric section of the carrying hub of the hose reel. Fig. 6 is an elevation of the right hand end of the structure of 75 Fig. 5.

Referring to the drawings there is shown a hollow pedestal 1 provided with a supporting base 2 and offset from one side of this pedestal is a substantially cylindrical casing 3 having its center close to the top of the pedestal 1 and therefore rising to a considerable height above the pedestal. One face of the casing is in the form of a removable plate 4, whereby access to the 85 casing throughout substantially its whole area is provided.

Formed on the pedestal 1 at a point corresponding to the center of the casing 3 is a boss 5 provided with a tapped socket 6 90 on the inner face into which is screwed a threaded stud 7 formed on one end of an elongated spindle 8 reaching to a point close to the inner face of the plate 4.

Extending axially through the spindle 8 95 from the outer end of the stud 7 to a point about midway of the length of the spindle is a passage 9 terminating in a radial extension 10 opening at the outer surface of the spindle 8 at a point which may be approximately midway of its length, although exactitude in this respect is of no particular moment.

Mounted on the spindle 8 is a hub 11 somewhat shorter than the spindle and provided 105 with an axial counterbore 12 extending from one end of the spindle to a point near the other end where the counterbore terminates

in a shoulder 13. The inner wall of the counterbore 12 remote from the shoulder 13 is formed with screw threads 14 for the reception of a gland 15.

5 Lodged in the counterbore 12 about the spindle 8 is a sleeve 16 of somewhat larger internal diameter than the spindle 8 and having its outer surface for the greater portion of its length of reduced diameter to 10 provide terminal outstanding flanges 17 whereby the main portion of the sleeve 16 is spaced on the outside from the inner wall of the hub and on the inside from the spindle 8. The outer ends of the sleeve 16 15 are recessed, as shown at 18, and the inner end of the gland 15 is recessed, as shown at 19, to receive and hold packing 20 within the chamber 12 between the gland 15 and corresponding end of the sleeve 16 and between the other end of the sleeve 16 and the shoulder 13, such packing bearing 20 against the inner wall of the hub where counterbored and the outer wall of the spindle 8. The sleeve is provided with a 25 passage 21 through its wall so that the continuation 10 of the passage 9 is always in communication with the chamber 12 where surrounding the sleeve 16.

One side of the hub 11 is formed with a 30 radial enlargement 22 into which is screwed one end of a hose nipple 23. Extending through the enlargement 22 in substantially parallelism with the axis of the hub 11 is a passage 24 communicating with the nipple 35 23 and normally closed at its outer end with a plug 25 or otherwise. The passage 23 is provided with a continuation 26 opening into the chamber 12.

On the exterior of the hub 11 there is 40 formed a radial flange 27 to which is attached a hose reel 28 conveniently formed of sheet metal fitted to the hub 11 and made fast by rivets 29 or otherwise to the flange 27. The reel is provided with an annular 45 channel portion 30 shaped to receive hose 31 when rolled up on itself into spiral form, and one end 32 of this hose is made fast to the hose nipple 23, which latter may be of customary shape for the purpose. The 50 other end of the hose is carried through an outlet funnel or neck 33 formed on the casing 3 at one side and preferably at a point higher than the middle of the casing. The walls of the neck 33 are rounded so as 55 to offer no obstruction to movements of the hose into and out of the casing. That end of the hose remote from the nipple end 32 is provided with a connection 34 which may be of convenient form for attachment to the 60 inner tube nipple of a pneumatic tire, or to receive any suitable form of nozzle, or generally to provide an outlet for fluid passing through the hose. The connection 34 may be of the automatic cut-off type which opens on application to an inner tube nipple, or

may be of any known and familiar type for the purpose.

The recess 6 in the boss 5 is made longer than the stud 7, so as to provide a cavity therein, and this cavity is entered by a passage 35 extending along the boss 5 from the interior of the pedestal and there the passage 35 has secured to it one end of a pipe 36 conveniently carried along the interior of the pedestal 1 to a low point where it 70 may be held in a lug 37 close to the base 2 and terminates in a coupling 38. In the lower end of the pedestal 1 adjacent to, or even encroaching on the base 2, is an opening 39 which may or may not be closed by a suitable cover, and through this opening there is introduced a pipe 40 made fast to the coupling 38 and coming from some convenient supply of fluid under pressure, which fluid may be air or water, but which 75 in most cases is air.

The pedestal 1 at an intermediate point in its height has another boss 41 thereon and into this boss is screwed one end of a stud 42 constituting a spindle upon which 90 there is mounted a spring drum 43 having its peripheral portion in the form of a spiral or fusee 44. Within the drum 43 there is formed a chamber 45 containing a spiral spring 46 having one end secured to the 95 drum 43, as indicated at 47, and the other end secured to the stud 42, as indicated at 48.

A chain 49 is wrapped around the fusee portion of the spring drum 43 being connected thereto at one end 50, while the other end of the chain is carried about the hub 11 and made fast thereto, as indicated at 51. The arrangement is such that with the spring 46 under a certain tension it tends to 100 wind the chain 49 upon the drum and at the same time through the chain turn the hub 11 and hose reel 28, so as to wind the hose thereon until the end 34 is in close relation to or even lodged within the neck or funnel 33. In Fig. 1 the end 34 of the hose is shown 105 slightly withdrawn from the neck in order to better display it, but normally it is contained within the neck, although within accessible position.

Communicating at one end with the passage 35 is a pipe 52 extending within the casing 3 to the top thereof where it enters the upstanding extension 53 of the casing, said extension carrying an indicator 54 with which the corresponding end of the pipe 52 115 is connected.

In the normal condition of the parts the hose 31 is wound upon the reel 28 with the greater portion of the chain 49 upon the fusee and the spring 46 under considerable 120 but reduced tension. The pipes 40 and 36, as well as the hose, are charged with air under pressure and this air finds its way through the pipe 52 to the gage or indicator 54, so that the observer may ascertain the 125 130

available pressure of air. The pipe 36 is in constant communication with the hose by way of the recess 6, passages 9 and 10, opening 21, chamber 12 and passages 26 and 24, 5 which latter communicate with the hose through the nipple 23.

If, now, it is desired to supply an automobile tire with air, it being assumed that the pressure in the various pipes is sufficient, 10 the hose is drawn out from the reel casing, thus causing the reel to rotate, which it may do without interference with communication between the hose and source of air supply, and such rotation causes a winding of the 15 chain 49 upon the hub 11 and an unwinding of the chain from the fusee, so that as the chain is unwound from the fusee and increased tension is caused in the spring, the winding leverage of the spring is increased, 20 whereby the applied force necessary is practically constant. When the hose is released the spring immediately comes into action to turn the fusee in the opposite direction, thus winding the chain thereon and in turn unwinding it from the hub 11, causing the reel to turn in a direction to wind the hose thereon. There is therefore provided an automatically operating structure tending at all 25 times to keep the hose wound upon the reel 30 out of the way and out of danger of injury and also ready for instant use when needed.

The pedestal, base and casing or housing may be made in the main in the form of a casting with the face plate 4 and the cover 35 for the opening 39 when provided made separately from the casting, so that the main portion of the structure need not include more than three pieces, or if the covering for the opening or hand hole 39 be omitted, the 40 body of the structure need consist of but two pieces. The hose reel can be conveniently made of sheet metal, while the hub 11 may be a casting properly cored and bored.

The spring may be of a size to cause about 45 two revolutions of the spring drum and with the reel hub properly proportioned to the drum the hub and the reel thereon will make about seven or eight revolutions, so that such a movement will cause a winding up of 50 thirty-five to forty feet of hose, such length of hose being ample for the purpose, and permitting the use of the hose either for blowing or washing purposes all about an automobile.

55 What is claimed is:—

1. A hose reel structure comprising a carrier, a spindle on the carrier provided with a fluid conducting passage, a hose reel having a hub portion mounted and rotatable on the spindle and provided with a fluid conducting passage for connection to a supply of fluid and to hose on the reel, and a fusee spring drum on the carrier provided with flexible connections to and windable 60 upon the hub of the hose reel to provide
- yieldable means for rewinding hose on and connected to the drum when said hose is withdrawn from the drum.

2. A hose reel structure comprising a support in the form of a hollow standard, a 70 stationary spindle on and inclosed by and fast to one end of the standard and when in the installed position extending substantially horizontally, said spindle being provided with an axial internal passage for 75 fluid under pressure, a hose reel having a hub mounted on the spindle for rotation thereon and provided with a bore communicating with the internal passage of the spindle, a casing on one side of the standard 80 inclosing the reel, hose connections on the reel communicating with the bore of the hub, and a fusee spring drum and flexible connections therefrom to and windable upon the hub of the hose reel and housed 85 in the standard.

3. A hose reel structure comprising a carrier having one end adapted to be fixed to a support, a spindle on the other end of the carrier and provided with a fluid conducting passage, said spindle being arranged to extend substantially horizontally when in the installed position, a hose reel having a hub portion mounted and rotatable on the spindle and provided with a fluid conducting passage for connection to a supply of fluid and to hose on the reel, and means on the carrier having flexible connections to and windable upon the hub of the hose reel and having a normal tendency to rotate the 90 reel in a direction to wind hose thereon and yieldable to the withdrawal of hose from the reel.

4. A hose reel structure comprising a carrier or support, a stationary spindle on and fixed to the support and extending horizontally in the installed position of the support, said spindle having a passage extending from one end part of the way through it and opening at the surface of 105 the spindle, means for the connection of a supply of fluid under pressure to the passage in the spindle, a hub mounted for rotation on the spindle and having an interior chamber communicating with the passage 110 through the spindle, said hub having a hose connection communicating with the chamber, a hose reel carried by the hub and adapted to have a hose wound thereon with one end fast to the hose connection and the 115 other end accessible, and packing means within the hub about the spindle, said packing including a spacing sleeve within the interior chamber and a gland carried by the hub and surrounding the end of the spindle 120 remote from the end fixed to the support.

5. A hose reel structure comprising a hollow pedestal with a substantially cylindrical casing supported thereon to one side of said pedestal with the center of the casing at ap- 130

proximately the upper end of the pedestal, a stationary spindle carried by and fixed to the pedestal and extending into the casing in the axis thereof, said spindle having a 5 passage extending from one end part way through it and opening at the surface of the spindle, means for the connection of a supply of fluid under pressure to the passage in the spindle, a hub mounted for rotation on the spindle and having an interior 10 chamber communicating with the passage through the spindle, said hub being provided with a hose connection communicating with said chamber, a hose reel carried by 15 the hub, a hose fast at one end to the hose connection and normally wound on the reel with the other end accessible at one side of the casing, and a spring and spring drum mounted in the pedestal and connected to 20 the hub for actuating the reel in a direction to wind the hose thereon.

6. A hose reel structure comprising a casing and a pedestal support therefor, a stationary spindle carried by and fixed to the 25 pedestal and extending into the casing, a hub rotatably mounted on the spindle and having an axial bore of greater diameter, a sleeve with flanged ends housed in the hub, packing engaging the ends of the sleeve, 30 and a packing gland entering the hub at one end, said hub being provided with a hose connection communicating with the interior of the hub where housing the sleeve, and the spindle having a passage therethrough 35 communicating with the interior of the hub where housing the sleeve, means within the pedestal for supplying fluid under pressure to the passage in the spindle, a spring in the pedestal provided with a spring drum and 40 connections therefrom to the hub, a hose reel mounted on the hub and rotatable therewith, and a hose carried by and adapted to be wound upon the reel and having one end connected to the hose connection on the hub.

45 7. A hose reel structure comprising a casing and a pedestal support therefor, a stationary spindle carried by and fixed to the pedestal and extending into the casing, a hub rotatably mounted on the spindle and 50 having an axial bore of greater diameter, a sleeve with flanged ends housed in the hub, packing engaging the ends of the sleeve, and a packing gland entering the hub at one end, said hub being provided with a hose con-

nection communicating with the interior of 55 the hub where housing the sleeve, and the spindle having a passage therethrough communicating with the interior of the hub where housing the sleeve, means within the pedestal for supplying fluid under pressure 60 to the passage in the spindle, a spring in the pedestal provided with a spring drum, and connections therefrom to the hub, a hose reel mounted on the hub and rotatable therewith, and a hose carried by and adapted 65 to be wound upon the reel and having one end connected to the hose connection of the hub, the other end of the hose reel being provided with a connection member and the casing having an opening through one side 70 for the passage of the hose.

8. A hose reel structure comprising a casing and a pedestal support therefor, a stationary spindle carried by and fixed to the pedestal and extending into the casing, a 75 hub rotatably mounted on the spindle and having an axial bore of greater diameter, a sleeve with flanged ends housed in the hub, packing engaging the ends of the sleeve, and a packing gland entering the hub at one 80 end, said hub being provided with a hose connection communicating with the interior of the hub where housing the sleeve, and the spindle having a passage therethrough 85 communicating with the interior of the hub where housing the sleeve, means within the pedestal for supplying fluid under pressure to the passage in the spindle, a spring in the pedestal provided with a spring drum and connections therefrom to the hub, a hose 90 reel mounted on the hub and rotatable therewith, and a hose carried by and adapted to be wound upon the reel and having one end connected to the hose connection on the hub, the other end of the hose reel being 95 provided with a connection member and the casing having an opening through one side for the passage of the hose, said casing also 100 being provided with a gage and connections therefrom to the means for supplying fluid under pressure.

In testimony that I claim the foregoing as my own, I have hereto affixed my signature in the presence of two witnesses.

CHARLES D. McCONNELL.
